UNITED STATES PATENT OFFICE

159,176

CONDIMENT DISPENSING UNIT

Paul B. Utley, Memphis, Tenn., assignor of forty per cent to (Mrs.) Lee N. Utley, ten per cent to Lola P. Utley, and ten per cent to Ben Utley, all of Memphis, Tenn.

Application December 16, 1948, Serial No. 150,198

Term of patent 3½ years

(Cl. D44—22)

To all whom it may concern:

Be it known that I, Paul B. Utley, a citizen of the United States, residing at Memphis, in the county of Shelby and State of Tennessee, have invented a new, original, and ornamental Design for a Condiment Dispensing Unit, of which the following is a specification, reference being had to the accompanying drawing, forming part thereof.

The figure is a perspective view of a condiment dispensing unit, showing my new design.

I claim:

The ornamental design for a condiment dispensing unit, as shown.

PAUL B. UTLEY.
